DESIGN FOR AN AUTOMOBILE

James E. Kepperley, Jr., Toledo, Ohio

Application February 3, 1934, Serial No. 50,603

Term of patent 14 years

To all whom it may concern:

Be it known that I, JAMES E. KEPPELLEY, JR., a citizen of the United States, residing in the city of Toledo, county of Lucas, and State of Ohio, have invented a new, original, and ornamental Design for Automobile, of which the following is a specification, reference being had to the accompanying drawing, forming part thereof.

In the drawing, Figure 1 is a side view of the automobile showing my new design.

Figure 2 is a perspective view of the automobile shown in Figure 1.

My design is characterized by the position of the V shaped windshield disclosed herein which involves the configuration of the body in the region adjacent the windshield of the automobile.

I claim:

The ornamental design for an automobile substantially as shown and described.

In testimony whereof, I affix my signature, this 1st day of February, 1934.

JAMES E. KEPPELLEY, JR.
